UNITED STATES PATENT OFFICE.

JOHN F. TINER, OF SUTHERLAND SPRINGS, TEXAS, ASSIGNOR OF ONE-HALF
TO H. WASHINGTON TALLY AND EUGENE A. WARREN, OF SAME PLACE.

DESIGN FOR A NUT-LOCK WASHER.

SPECIFICATION forming part of Design No. 33,639, dated December 4, 1900.

Application filed August 28, 1900. Serial No. 28,363. Term of patent 14 years.

To all whom it may concern:

Be it known that I, JOHN F. TINER, a citizen of the United States, residing at Sutherland Springs, in the county of Wilson and State of Texas, have invented and produced a new and original Design for Nut-Lock Washers, of which the following is a specification, reference being had to the accompanying drawings, forming part thereof.

10 Figure 1 is a perspective view of my invention. Fig. 2 is a top plan view of the same. Fig. 3 is a bottom plan view of the same.

As shown in the drawings, the leading or material feature of my design consists of the 15 circular plate A, having a central circular opening a to receive the bolt and having a

tooth a' projecting inwardly into said opening, five chordwise kerfs or narrow slots b extending inwardly from the circumference of the plate. The points c, formed by said kerfs, are 20 beveled on their under sides at c'.

Having thus described my invention, what I claim as new, and desire to secure by Letters Patent, is—

The design for a nut-lock washer, as herein 25 shown and described.

In testimony whereof I affix my signature in presence of two witnesses.

JOHN F. TINER.

Witnesses:

J. D. FERGUSON,
W. J. FERGUSON.
